US00D799464S

(12) **United States Design Patent** (10) **Patent No.:** **US D799,464 S**
(45) **Date of Patent:** **** Oct. 10, 2017**

(54) **COMBINED WATCH HOLDER AND SMARTPHONE STAND**

(71) Applicant: **Hu Zaihui**, Shenzhen (CN)

(72) Inventor: **Hu Zaihui**, Shenzhen (CN)

(73) Assignee: **MPOW TECHNOLOGY CO., LTD**,
Kowloon (HK)

(**) Term: **15 Years**

(21) Appl. No.: **29/557,264**

(22) Filed: **Mar. 8, 2016**

(51) LOC (10) Cl. **14-03**

(52) U.S. Cl.

USPC **D14/252**
